PUSHPIN

Lewis S. Krantz, Waterbury, Conn.

Application October 20, 1933, Serial No. 694,441

3 Claims. (Cl. 85—53)

This invention relates to push pins or thumb tacks, and more particularly to a push pin having a non-breakable head.

A further object is to provide a push pin of the above nature in which the head is made of molded or fabricated flexible tough material, such as celluloid, and which will permit the pin to be driven into a wall or other support by a hammer or similar instrument without breaking or shattering.

10 A further object is to provide a push pin of the above nature in which a hardened steel pin is embedded in the flexible head in such a manner that it will be securely held in position.

15 A further object is to provide a device of the above nature which will be simple in construction, inexpensive to manufacture, easy to manipulate, compact, ornamental in appearance, and very efficient and durable in use.

With these and other objects in view there has 20 been illustrated on the accompanying drawing, one form in which the invention may be conveniently embodied in practice.

In the drawing:

25 Fig. 1 represents a perspective view of the improved non-breakable push pin.

Fig. 2 is a vertical sectional view through the same.

Fig. 3 is a detail perspective view of the steel pin employed.

30 Previous forms of "push pins" now on the market were provided with glass heads in which the steel pin was either embedded during the process of molding the glass, or cemented in a hollow socket formed in the head. Such constructions 35 were not only expensive to manufacture but were subject to the disadvantage that the glass head was likely to crack or splinter during the cooling after the molding process, or while the pin was being pushed into the wall. In the type where 40 the pin was cemented in place, the cement was quite apt to loosen and cause the head to fall off.

45 By means of the present invention, the above and other disadvantages have been avoided, and a push pin has been provided in which the head not only is unbreakable, but cannot possibly fall off the pin.

50 Referring now to the drawing in which like reference numerals denote corresponding parts throughout the several views, the numeral 10 indicates the head of a push pin, and 11 the pointed pin affixed thereto. The head 10 is made substantially spool-shaped in form and is preferably constructed of transparent or translucent celluloid, but heads of other non-breakable flexible material, either colored or opaque, may be

employed within the spirit of this invention. The celluloid head may be either formed in a mold or turned out on a lathe from a celluloid rod. The pin 11 is preferably made of steel and is provided with a pointed end 12 and a blunt end 13, the latter being preferably formed by swaging to produce a pair of opposed flattened sections 14, the width of which is greater than the diameter of the shank 15 of said pin adjacent thereto. After the swaging operation, the entire pin is preferably hardened by a suitable heat treatment to toughen it.

5 The hardened pin 11 is attached to the head 10 by driving the blunt end 13 thereof by the use of suitable tools, not shown, into the base of the 10 head 10, which may be held by other suitable tools. The flexible nature of the celluloid head permits the entrance of the blunt end 13 of the pin without distorting the outer shape of the head 10. After the insertion of said pin to the 15 desired depth, the surrounding material of the celluloid will close in about the tapering rounded shank portion of the pin, which is smaller in diameter than the width of the blunt end 13. A 20 secure anchorage for the embedded pin will thus be formed, and it will be understood that it will be practically impossible for the head to fall off 25 the pin in use.

While there has been disclosed in this specification one form in which the invention may be embodied, it is to be understood that this form is shown for the purpose of illustration only, and that the invention is not to be limited to the specific disclosure but may be modified and embodied in various other forms without departing 30 from its spirit. In short, the invention includes 35 all the modifications and embodiments coming within the scope of the following claims.

Having thus fully described the invention, what 40 is claimed as new, and for which it is desired to secure Letters Patent, is:

1. In a push pin, a head of flexible non-shatterable material, and a hardened steel pointed pin having an enlarged blunt end embedded in said 45 head, said pin being driven into the solid material of and anchored in said head by the automatic closing in of the flexible material of said head around the intermediate smaller section below said blunt end.

50 2. In a push pin, a celluloid head, a pointed steel tapered pin having a broadened flattened blunt end, said broadened portion being embedded in the celluloid material of said head by driving it into a solid portion thereof and being anchored 55

in place by the natural closing in of said celluloid around the smaller intermediate section of said pin below said blunt end.

3. In a push pin, a head of flexible non-shatterable material, and a hardened steel pointed pin having an enlarged out-of-round end embedded

in said head, said pin being driven into the solid material of said head and anchored in said head by the natural closing in of the flexible material of said head around the intermediate smaller section below said end.

LEWIS S. KRANTZ.
